United States Patent Office

Des. 193,855
Patented Oct. 16, 1962

193,855

MONSTRANCE

Arlene Bauer, 3221 S. Superior St., Milwaukee, Wis.

Filed Nov. 8, 1961, Ser. No. 67,415

Term of patent 14 years

(Cl. D29—23)

FIG. 1 is a front view in elevation of a monstrance embodying my design.

FIG. 2 is a side view in elevation thereof.

FIG. 3 is a cross-sectional view taken on the lines 3—3 of FIG. 1.

I claim:

The ornamental design for a monstrance, as shown.
